HIS ATTORNEY

UNITED STATES PATENT OFFICE

VITUS HRUBES, OF BRITTON, SOUTH DAKOTA

ROLLER SKATE

Application filed July 6, 1929. Serial No. 376,314.

This invention relates to certain novel improvements in roller skates and has for its principal object the provision of an improved construction of this character which will be highly efficient in use and economical in manufacture.

The salient object of my invention is to provide a roller skate which will have certain of the wheels thereon arranged so that they may be rotated in but one direction.

Another object of the invention is to provide a novel arrangement for lubricating a device of the above described character.

Other objects will appear hereinafter.

15 The invention consists in the novel combination and arrangement of parts to be hereinafter described and claimed.

The invention will be best understood by reference to the accompanying drawing, 20 showing the preferred form of construction and in which:

Fig. 1 is a side elevational view of a preferred form of construction for my invention mounted at the front of a roller skate 25 which is fragmentally illustrated;

Fig. 2 is an edge view of a preferred form of construction for my invention;

Fig. 3 is a sectional view taken substantially on the line 3—3 of Fig. 2;

30 Fig. 4 is a sectional view taken substantially on the line 4—4 on Fig. 3; and

Fig. 5 is a detail view depicting the means employed for preventing rotation of the wheel in one direction.

35 In the accompanying drawing wherein I have illustrated a preferred form of construction for my invention 10 indicates the front portion of a roller skate which has a structure 11 depending therefrom in which an axle 12 is fixed. Associated with the skate 10 is the usual clamping structure 13 which is employed for connecting the skate 10 to the user's shoe.

40 Rotatably mounted on the axle 12 is a wheel 14 which may be either of the plain bearing type or which may have suitable anti-friction bearings associated therewith in the manner well understood in the art. On the 45 outwardly disposed face of the wheel 14 I

provide the circular ratchet 15, the utility of which will be set forth presently.

Fixed on the axle 12 exteriorly of the wheel 14 is a bracket 16 which is retained in position through the medium of the set screw 17. 55 The bracket 16 includes a portion which is disposed above the circular ratchet 15 and in this portion a stud 18 is journaled on which a pawl 19 is fixed which is intended to engage the teeth of the circular ratchet 15. 60 The pawl 19 is held against the teeth of the ratchet 15 by the spring 20 which has an end portion which is disposed above said pawl and the opposite end of the spring is fixed on the arm 16. It is, therefore, manifest that the 65 wheel 14 may be rotated in one direction and that the pawl 19 will slide over the teeth. However, rotation of the wheel 14 in the opposite direction will cause the pawl 19 to engage in one of the teeth and in this manner 70 rotation of the wheel 14 will be prevented.

Mounted on the bracket 16 adjacent the pawl 19 is a lubricating mechanism generically indicated by 21 which includes a substantially conical member which is preferably 75 formed from felt or the like. A lubricant such as oil is introduced onto this substantially conical member and this lubricant is fed as required onto the pawl 19 and subsequently onto the ratchet 15 and this arrangement also lubricates the mounting of the pawl 19.

80 A cap 23 is provided which is substantially dish shaped and which has a flange 24 provided adjacent the open face thereof. Suitable securing elements 25 are extended through this flange 24 and serve to retain the cap 23 in position over the bracket 16 and the parts associated therewith and thus protect these elements from foreign matter and the 85 like.

85 It is manifest from the foregoing description that I have provided a construction which will permit free rotation of the wheel of a roller skate in one direction but which 90 will prevent rotation of the wheel in the opposite direction. This arrangement will obviously aid in the operation of the skate. It is also apparent that the device is arranged so 95 that the operating parts may be expeditiously 100

lubricated and also so that dust and other foreign matter will be prevented from coming in contact with the operating parts.

It is preferable that a wheel construction such as the foregoing be associated with the front axle of a roller skate since the construction will be of greater aid in the operation of the skate when it is mounted in such a position but it is to be understood that the arrangement might be associated with any of the wheels of the roller skate without departing from the purview of my invention.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In combination with the axle of a roller skate or the like, a wheel rotatably mounted on said axle, a clamp structure mounted on said axle in juxtaposition to said wheel, a pawl carried by said clamping structure, a ratchet on said wheel adapted to be engaged by said pawl whereby to prevent rotation of said wheel in one direction while permitting free rotation of said wheel in the opposite direction.

2. In combination with the axle of a roller skate or the like, a wheel rotatably mounted on said axle, a clamp structure mounted on said axle in juxtaposition to said wheel, a pawl carried by said clamping structure, a ratchet on said wheel, means carried by said clamp structure for forcing said pawl into engagement with said ratchet whereby to prevent rotation of said wheel in one direction while permitting free rotation of said wheel in the opposite direction.

3. In combination with the axle of a roller skate or the like, a wheel rotatably mounted on said axle, a clamp structure mounted on said axle in juxtaposition to said wheel, a pawl carried by said clamping structure, a ratchet on said wheel, means carried by said clamp structure for forcing said pawl into engagement with said ratchet whereby to prevent rotation of said wheel in one direction while permitting free rotation of said wheel in the opposite direction, and lubricating means carried by said clamp structure.

4. In combination with the axle of a roller skate or the like, a wheel rotatably mounted on said axle, a clamp structure mounted on said axle in juxtaposition to said wheel, a pawl carried by said clamping structure, a ratchet on said wheel, means carried by said clamp structure for forcing said pawl into

engagement with said ratchet whereby to prevent rotation of said wheel in one direction while permitting free rotation of said wheel in the opposite direction, and a housing carried by said wheel enclosing said clamp structure and the means carried thereby.

5. In combination with the axle of a roller skate and a wheel rotatably mounted thereon, a ratchet on the outer face of said wheel, a bracket mounted on said axle exteriorly of said ratchet, and including a portion projecting over the periphery of said ratchet, a stud in said last named portion, a pawl on said stud adapted to engage the teeth of said ratchet, and a spring for urging said pawl against the teeth of the ratchet, said spring having one end bearing upon said pawl and having the other end thereof fastened to said bracket.

In testimony whereof I affix my signature.

VITUS HRUBES.
